CLOTHES RACK FOR VEHICLES

James D. Patton, Windber, Pa.

Application July 8, 1949, Serial No. 103,657

3 Claims. (Cl. 224—42.45)

1

This invention relates to clothes racks for vehicles.

An object of this invention is to provide a rack or support for clothes, which can be easily and quickly mounted on the back seat of a vehicle without the use of tools and without marring the upholstery.

Another object of this invention is to provide a device of this kind which will support the clothes in a manner so that the clothes will not be wrinkled.

A further object of this invention is to provide a device of this kind which in one form thereof will permit at least a partial use of the back seat, the device being extensible and provided with horizontally adjustable hooks for clothes hangers.

With the above and other objects in view, my invention consists in the arrangement, combination and details of construction disclosed in the drawing and specification, and then more particularly pointed out in the appended claims.

In the drawings,

Figure 1 is a detail front elevation of a clothes rack or hanger constructed according to an embodiment of this invention, showing the device in applied position on the back seat of a vehicle, the latter being broken away,

Figure 2 is a sectional view taken on the line 2—2 of Figure 1.

Figure 3 is a sectional view taken on the line 3—3 of Figure 2.

Figure 4 is a plan view of one of the garment supporting members,

Figure 5 is a detail front elevation, partly broken away and in section, of a modified form of this invention,

Figure 6 is a sectional view taken on the line 6—6 of Figure 5,

Figure 7 is a sectional view taken on the line 7—7 of Figure 6,

Figure 8 is a perspective view of another modification of this invention.

Referring to the drawings and first to Figures 1 to 4 inclusive, the numeral 10 designates generally the back of the rear seat of a vehicle, and the numeral 11 designates the ledge or shelf which is normally disposed back of the back 10 and below the upper edge of the latter.

In order to provide a means whereby garments may be supported in dependent relation from the upper portion of the back of the rear seat with the garment lying flat against the back 10 and extending over the seat, I have provided an elongated bar 12 which is adapted to engage

5

2

against the forward side of the back 10. The bar 12 is preferably curved in transverse section with the concave side 13 thereof rearmost for snug engagement against the convex forward side 14 of the seat back 10.

The bar 12 is supported in horizontal position by means of a pair of resilient supporting rods or wires 15 which are of substantially U-shape and are formed at their forward lowermost ends with eyes 16 engageable with screw eyes 17 carried by the bar 12. The bar clamping wires or members 15 extend over the upper edge of the seat back 10 and are secured by fastening means 18 to an upper or rear clamping bar 19. The upper or rear clamping bar 19 is adapted to engage on the shelf or ledge 11 and to bear against the rear side of the seat back 10, as shown in Figure 2.

55

A plurality of garment hanger supporting lugs 21 are carried by the bar 12 at adjusted points therealong, and each lug 21 includes a base 22 disposed in face abutting relation to the forward side of the bar 12. The base 22 has extending from the upper end thereof an inverted V-shaped hook or clamping member 23 engageable over the tapered upper edge 24 of the bar 12. A forwardly projecting arm or lug 25 extends from the base 22 and is provided on its upper edge with a plurality of notches 26 within which the hooks or garment hangers are adapted to engage.

Referring now to Figures 5, 6 and 7, there is disclosed a modified form of this invention which includes an extensible horizontally disposed member generally designated as 27, which is formed of telescoping tubular members 28 and 29. The tubular members 28 and 29 have mounted thereon garment hanger supporting lugs 21a similar in every detail to the lugs 21, and the supporting member 27 is supported on the forward side of the seat back 10a by means of resilient supporting wires or rods 15a. A rear clamping bar 30 is secured to the resilient members 15a and is formed of telescoping tubular members 31 and 32. With a construction as shown in Figures 5, 6 and 7, the device may be collapsed to be of relatively short length in order to permit at least one person to be seated in the rear seat of the vehicle, whereas with the structure shown in Figures 1 to 4, it is contemplated that the rear seat be unoccupied.

Referring now to Figure 8, there is disclosed a single hanger comprising a lug 21b similar to lug 21, which has fixed thereto or formed integral therewith a resilient support 15b, and the rear

end of support 15b has fixed thereto or formed integral therewith a clamping member 19b.

In the use of this device, the bar 12 is disposed against the forward side of the seat back 10 with the bar 19 engaging on the rear upper side of the back 10 and resting on the ledge 11. The hanger supporting members 21 are adjusted lengthwise of the supporting bar 12 and the garment hanger may then be engaged in selected notches 26 of the lugs 25. The garments supported by this device will lie flat against the forward side of the seat back and may drape downwardly over the seat.

With a structure as hereinbefore described, the garments need not be folded and will not become wrinkled as is the case where they are packed in suit cases or the like.

I do not mean to confine myself to the exact details of construction herein disclosed but claim all variations falling within the purview of the appended claims.

What I claim is:

1. A clothes rack for mounting on the back of a vehicle seat comprising an elongated horizontal bar, a second elongated horizontal bar, longitudinally bent resilient means pivotally connecting said bars together and adapted to engage over the upper edge of the seat back, and hanger supporting lugs carried by one of said bars.
2. A clothes rack for mounting on the back of a vehicle seat comprising an elongated hori-

zontal bar, a second elongated horizontal bar, longitudinally bent resilient means pivotally connecting said bars together and adapted to engage over the upper edge of the seat back, a plurality of hanger supporting lugs, and hooks carried by said lugs engaging over an edge of one of said bars.

3. A clothes rack for mounting on the back of a vehicle seat comprising an elongated extensible horizontal bar, a second elongated extensible horizontal bar, longitudinally bent resilient means pivotally connecting said bars together and adapted to engage over the upper edge of the seat back, and hanger supporting lugs carried by one of said bars.

JAMES D. PATTON.
